US00D920360S

(12) **United States Design Patent** (10) Patent No.: **US D920,360 S**
(45) Date of Patent: **** May 25, 2021**

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA
(US); **Erica L. Clymer**, Northampton,
PA (US); **Shenchi Tian**, Easton, PA
(US)

(73) Assignee: **Lutron Technology Company LLC**,
Coopersburg, PA (US)

(**) Term: **15 Years**

(21) Appl. No.: **29/707,327**

(22) Filed: **Sep. 27, 2019**

Related U.S. Application Data

(63) Continuation of application No. 29/663,983, filed on
Sep. 20, 2018, now Pat. No. Des. 866,588, which is
a continuation of application No. 29/607,668, filed on
Jun. 15, 2017, now Pat. No. Des. 830,409.

(57) **CLAIM**

The ornamental design for a display screen or portion
thereof with graphical user interface, as shown and
described.

DESCRIPTION

The file of this patent contains at least one drawing/photograph
executed in color. Copies of this patent with color
drawing(s)/photograph(s) will be provided by the Office
upon request and payment of the necessary fee.

The sole FIGURE shows a display screen or portion thereof
with graphical user interface showing our new design.
The peripheral dashed broken lines illustrate a display
screen or portion thereof, and form no part of the claimed
design.
